CLAIM

I claim the ornamental design for the tablet case, as shown and described.

DESCRIPTION

FIG. 1 is a perspective view of a tablet case showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a rear, right perspective view thereof.

The broken lines visible in FIGS. 1 and 2 represent stitching and are part of the claim.
